UNITED STATES PATENT OFFICE.

EDGAR W. BOWEN, OF DETROIT, AND ROBERT TURNER, OF HIGHLAND PARK, MICHIGAN, ASSIGNORS TO D. M. FERRY & COMPANY, OF DETROIT, MICHIGAN, A CORPORATION OF MICHIGAN.

DISPLAY APPARATUS.

1,387,965.

Specification of Letters Patent. Patented Aug. 16, 1921.

Application filed September 23, 1920. Serial No. 412,310.

To all whom it may concern:

Be it known that we, EDGAR W. BOWEN and ROBERT TURNER, citizens of the United States, and residing at Detroit and Highland Park, respectively, county of Wayne, and State of Michigan, have invented a new and Improved Display Apparatus, of which the following is a specification.

This invention relates to means for displaying for sale a maximum number of small articles, packages of seeds preferred, and consists of a case having a front door hinged at its upper edge to the top of the case and adapted to be swung up and back until it lies on said top, shelves being provided within the case which are disclosed when the front door is swung back.

It also consists in knock-down display boxes which are placed upon the shelves when the filled case is to be shipped, and in folding supports pivoted to the inner side of the front door and adapted to be swung up to vertical position to support the display boxes when the front door is swung up and back and rests on the top.

It further consists in the details of construction illustrated in the accompanying drawings and particularly pointed out in the claims.

30 In the accompanying drawings, Figure 1 is a perspective view of our improved display apparatus. Fig. 2 is a central vertical transverse section of the apparatus when collapsed. Fig. 3 is a vertical section of one 35 of the folding supports and the end of a display box thereon. Fig. 4 is a longitudinal vertical section of the top of the box when the front door has been folded back.

Similar reference characters refer to like 40 parts throughout the several views.

The drawing shows a case consisting of the top 1, back 2, sides 3, bottom 4 and front 5. A front door 6 is hinged at its upper edge to the front edge of the cover, the 45 hinges permitting the door 6 to be swung up and back until it lies flat on the top as indicated in Fig. 1. These hinges are formed of narrow leaves 7 and 8 united by means of rectangular links 9 which permit 50 the door to freely assume the positions shown in Figs. 1 and 2. The case is provided with shelves 10 on which the display boxes 11 are placed when the space below the lower shelf has been filled. These display 55 boxes are fully described in the Turner

Patents No. 836,406 dated November 20, 1906 and No. 839,438 dated December 25, 1906.

A pair of supports is mounted on the inner face of the door 6 so that they may be 60 swung to vertical position, as shown in Fig. 1, after the door has been swung up to lie on the top 1. A base for each support is secured to the door 6 and preferably consists of a flat bar 12 having up-turned ears 13 at 65 its ends perforated to receive the pins 14 which extend through the small lugs 15 at the ends of the angle bar 16. Secured at their lower ends to one of these angle bars 16 are two legs 17 and 18 connected near 70 their upper ends by means of the angle stamping 19 which has an upwardly extending pin 20 adapted to enter a hole 21 in the bottom of one of the boxes 11 to position both the box and the support. The other 75 box 11 rests on the angle bars 16 between the supports.

The other support has legs 22 and 23, also secured to a lower angle bar 16 and an upper cross bar 19^a is provided with a pin 20 80 to enter a second hole in the bottom of the display box 11. It will be noticed that the two legs 22 and 23 are a short distance forward of the legs 17 and 18 respectively, so that the supports can be folded down together. The leg 22 has its middle portion 24 bent down out of alignment, as shown in Fig. 4, to permit the portion 25 of the cross bar 19 (Fig. 1) to extend across when the supports are folded down as shown in Figs. 90 2 and 4. This cross bar is preferably formed with a notch 26 to receive the straight upper portion of the leg 22.

In practice, at the factory, the space below the lower shelf 10 is filled with packages, the display boxes are collapsed as indicated in the above named Turner patents, and their several trays properly filled; these boxes are placed on the shelves 10 which they fit, and the door 6 is swung 100 down as indicated in Fig. 2 and secured with screws. The case and contents are ready for shipment. When the display cabinet is to be used, the boxes 11 are removed and opened out, as shown by the top 105 box in Fig. 1, the lower box being similarly opened, and these boxes are then mounted on the supports. The packages which were packed in the space below the shelves may now be arranged on these shelves so that 110

advantage may be taken of this additional display room. As the door lies flat against the top of the case, a firm foundation for the box supports is assured.

5 The details and proportions of the various parts of this display apparatus may all be changed by those skilled in the art, without departing from the spirit of our invention as set forth in the following claims.

10 We claim:—

1. In a display apparatus, a case having a front door hinged at its upper edge to the front edge of the top and adapted to be swung up and back to lie flat upon the top, 15 supports pivoted to the inner side of the door and adapted to be folded up to extend vertically when the door lies on the top, and display boxes mounted on the supports.

2. In a display apparatus, a case having 20 a front door hinged at its upper edge to the front edge of the top and adapted to be swung up and back and lie flat on the top,

a pair of bars secured to the inner side of the cover and having upturned ears, supporting frames, and pivots mounted in said 25 ears whereon the supporting frames are mounted.

3. In a display apparatus, a case having a door adapted to lie flat on the top of the case, a pair of supports pivoted to the inner 30 side of the door and adapted to lie against the door or be swung up to extend vertically therefrom, said supports being formed with shelves provided with upwardly extending projections, and display boxes adapted to 35 be mounted on said shelves when the supports are swung up to vertical position, said boxes having recesses to receive the projections on the shelves and the ends of the boxes engaging the uprights above said 40 shelves.

EDGAR W. BOWEN.
ROBERT TURNER.
